James Garrison Butterfield,

INVENTOR, BY
Louis Feuer & Co.,
Attn's.

UNITED STATES PATENT OFFICE.

JAMES G. BUTTERFIELD, OF SIOUX CITY, IOWA.

LOCOMOTIVE ASH-PAN.

SPECIFICATION forming part of Letters Patent No. 242,430, dated June 7, 1881.

Application filed July 9, 1880. (No model.)

To all whom it may concern:

Be it known that I, JAMES GARRISON BUTTERFIELD, of Sioux City, in the county of Woodbury and State of Iowa, have made certain Improvements in Ash-Pans and Fire-Boxes of Locomotives, &c., of which the following is a specification.

This invention relates to the ash-pans and fire-boxes of locomotives, &c.; and it consists in the arrangement of the grates upon a downwardly curved deflecting plate or support above a hollow ash-pan, whereby the falling cinders and ashes are caught and prevented from escaping, and the draft deflected downward and upward before it strikes the grate, as hereinafter set forth.

The invention further consists in hinging one end of the ash-pan, so that it may be adjusted higher or lower, or the pan cleaned from the outside, as hereinafter set forth.

The invention further consists in making the flaring ash-pan adjustable higher or lower by means of cams or similar devices, as hereinafter set forth.

The invention further consists in forming the coal-burning-grate support, cinder-chute, and deflecting-plate all in one piece of cast-iron, substantially as set forth.

I accomplish these results by the use of the mechanism illustrated by the accompanying drawings, in which—

Figure I is a plan view in section, the upper half on the line $x x'$ of Fig. II, and the lower half on the line $y y'$ of Fig. II. Fig. II is a longitudinal section, and Fig. III is a cross-section of the lower part of the fire-box and the ash-pit of a locomotive, showing my invention when applied to both coal and wood burners, the right-hand side showing the coal-burning grate, and the left-hand side showing the wood-burning grate.

A is the water-leg or lower part of the boiler, surrounding the fire-box; and B, the ash-pit, having the usual hinged dampers, $a a'$.

C is an ash-pan, made with flaring sides and ends, $b b'$, and mounted either upon feet c or cams d , one of each being shown, so that the pan may be suspended, either rigidly or adjustably, some distance above the bottom of the ash-pit, as hereinafter explained.

Above the ash-pan C is a downwardly-curved

deflecting or supporting plate, E', resting upon the projecting edge of the ash-pit B, and when coal-burning grates F' are used this curved plate will be provided with an inclined top, E², 55 in which the grate-bars are pivoted, as shown, and when used for burning wood a flange or rib, d', will be formed upon the top of the curved plate, to retain the grate-bars F² in place. 60

In both forms of the deflecting-plate the space between it and the leg A of the boiler will be filled with fire-clay, or other non-conducting material, to counteract any bad influences cold air might exert by entering at these 65 points.

When the coal-grates are used holes h are left in the top E² of the plate E', through which the fire-clay is inserted.

The grate-bars may be made in any desired 70 style or form, the bars F' on the right-hand side of the figures being of the ordinary "rocking" pattern used in coal-burning locomotives, while the bars F² on the left-hand side are the ordinary wood-burning pattern, the only 75 change required to use either being in the form of the upper side of the deflecting-plate E'.

The forward end, b', of the ash-pan C will be hinged at d², and provided with a system of levers, e¹ e² e³ e⁴, so that it may be dropped 80 down to enable the cinders and ashes to be removed through the damper a.

By these arrangements of the deflecting-plate E', grates F' or F², and ash-pan C, all danger from escaping sparks or live cinders is 85 avoided, as none can get out over the flaring edges of the pan C, while the curved plate E' turns them all into the pan.

A large percentage of partially-burned coal falls through the grates into the ash-pan C, 90 and is ordinarily wasted; but by this arrangement the entering air is deflected downward by the curved plate E' before it passes upward through the grates, and acts upon the burning cinders and keeps them alive until they are 95 entirely consumed, thus greatly economizing in fuel, as this combustion adds somewhat to the heat of the furnace, as well as to heat the air before it enters through the grates to form a "hot blast." This will be found very advantageous 100 in cold weather.

The centers of each of the sections of the

rocking grates F' will be provided with hang-
ers m, projecting downward and connected to
each other by a bar, n, so that they may be os-
cillated in concert.

5 H is a lever pivoted to the connecting-bar
n, and passing out through the lower part of
the deflecting-plate E' and leg A, and adapted
to be vibrated by a lever, H', from the cab of
the locomotive, to oscillate the grate-bars F' in
10 clearing them of ashes, cinders, &c.

Where the lever H passes through the plate
E' it is surrounded with a steam and water
tight bushing, t, to prevent leakage at this
point.

15 I am aware that it is not new to oscillate the
bars F' by levers running through the side or
bottom of the ash-pan and attached to one
side of the grate-bars; but, so far as I am aware,
none has ever been used with the operating-
20 lever attached to the center of the grate-bars,
and passing out through the leg of the boiler
at a point very nearly on a line with the con-
necting-bar n, by which means the strain is
evenly distributed over all parts of the bars,
25 and the line of angularity of the lever H
greatly reduced, whereby the grates are oscil-
lated with much less expenditure of force, and
with less strain upon the parts; hence they
may be made with less metal to produce the
30 same results.

The ash-pan C is shown with one end
mounted upon a stationary standard, c, while
the other is supported by an adjustable cam,
d. In some cases it may be found advan-
35 geous to use either method of supporting the
pan; hence I do not wish to confine myself to
either.

I am aware that it is not new to use a curved
deflecting-plate in connection with a flaring-

sided solid ash-pan; but none, so far as I am 40
aware, show them in connection with grates or
the adjustable end or ends b' of the ash-pan.

I am aware of the patent granted to Farley,
No. 134,741; but he shows no grate-bar, his
object being, mainly, to afford a means of pro-
tection from snow, &c. I do not claim any
such construction, as the grate-bar forms an
important element in my combination; but
45

What I do claim as new, and desire to secure
by Letters Patent, is—

1. The combination and arrangement, with
the grates F' or F², of the downwardly-deflect-
ing supporting-plate E' and the ash-pan C, hav-
ing flaring sides b b', substantially as and for
the purpose set forth. 50

2. The ash-pan C, having the inclined sides
and ends b b', with one or more of said sides
or ends b' vertically adjustable, in combination
with the downwardly-curved deflecting-plate
E', substantially as set forth. 55

3. The pan C, mounted upon cams or simi-
lar devices d, whereby it may be adjusted
higher or lower, in combination with the grates
F' F² and the downwardly-deflecting support-
ing-plate E', substantially as and for the pur-
pose set forth. 60

4. The ash-pan C, having the flaring sides
and ends, with one or more of said sides or
ends, b', adjustable, in combination with the le-
vers e' e² e³ e⁴, arranged and operating substan-
tially as hereinbefore set forth. 70

In testimony whereof I have hereunto set
my hand in the presence of two subscribing
witnesses.

JAMES GARRISON BUTTERFIELD.
